UNITED STATES PATENT OFFICE.

DONALD PATRICK MUSE, OF JUNCTION CITY, ARKANSAS.

ELECTRICAL PIANO ATTACHMENT.

1,229,122.

Specification of Letters Patent.

Patented June 5, 1917.

Application filed August 17, 1915. Serial No. 45,898.

To all whom it may concern:

Be it known that I, DONALD P. MUSE, a citizen of the United States, and a resident of Junction City, in the county of Union and State of Arkansas, have invented a new and Improved Electrical Piano Attachment, of which the following is a full, clear, and exact description.

The object of the invention is to provide 10 a new and improved musical instrument arranged to permit of playing several instruments such a violin, and orchestra bells, in harmony with a piano when playing the latter.

15 In order to accomplish the desired result use is made of a piano having the usual keys and sounding devices controlled by the keys, and actuating devices connecting the said piano keys with the sounding devices of the 20 other musical instruments to sound the latter in harmony with the piano on playing the keys thereof.

A practical embodiment of the invention is represented in the accompanying drawings forming a part of this specification, in which similar characters of reference indicate corresponding parts in all the views.

Figure 1 is a cross section of the musical instrument;

30 Fig. 2 is a diagrammatic view of the same;

Fig. 3 is a plan view of the keyboard of the piano and the circuit closer controlled by the keys;

35 Fig. 4 is an enlarged cross section of the same on the line 4—4 of Fig. 3;

Fig. 5 is a cross section of one of the end supports for the rail carrying the circuit closers;

40 Fig. 6 is an enlarged plan view of one of the violins, the fingering devices and the sounding devices for the same;

Fig. 7 is an enlarged sectional side elevation of the same on the line 7—7 of Fig. 6;

45 Fig. 8 is an enlarged cross section of the same on the line 8—8 of Fig. 6 and showing more particularly the sounding devices;

Fig. 9 is an enlarged sectional elevation of one of the revolving wheels for sounding 50 a violin string, the section being on the line 9—9 of Fig. 8;

Fig. 10 is a section on the line 10—10 of Fig. 8;

Fig. 11 is a similar view of the same on the line 11—11 of Fig. 8;

55

Fig. 12 is a plan view of the orchestra bells and the actuating devices thereof;

Fig. 13 is an enlarged cross section of the same on the line 13—13 of Fig. 12; and

Fig. 14 is a sectional side elevation of the 60 same on the line 14—14 of Fig. 13.

The piano A of usual construction is provided with strings B adapted to be sounded by the hammers C' of the piano action C controlled by the keys D. A rail E (see 65 Figs. 1, 3, 4 and 5) extends lengthwise within the piano casing directly above and near the rear ends of the keys D, and on the said rail E are mounted circuit closers F, one for each key and each normally open, each 70 circuit closer being adapted to be closed on pressing the corresponding key D. Each circuit closer F consists of a flat spring F' attached to the under side of a block F² of insulating material and adjustably secured 75 to the rail E by a screw F³ extending through a slot E' formed in the rail E. The free end of the spring F' rests on the rear end of the piano key D and when the latter is played then the spring F' is bent upward into engagement with a contact F⁴, preferably in the form of a screw secured on the corresponding block F². The upper end of the contact F⁴ is connected by a

80 branch wire G with a wire G' connected with 85 a suitable source of electrical energy G² (see Fig. 2), the same being shown as a cell of a storage battery. It is understood that all the branch wires G of the circuit closers for the several keys of the piano are 90 connected with the wire G'. Each of the springs F' is connected by a wire G³ with the electromagnet H which in turn is connected by a wire G⁴ with the electromagnet I connected by a wire G⁵ with the electro-

95 magnet J connected by a wire G⁶ with the battery G² to complete electric circuits adapted to be closed on playing the corresponding keys D of the piano. The electromagnets H, I and J are mounted in a 100

suitable frame or casing K adapted to support a number of instruments, such, for instance, as a violin L, and orchestra bells N, adapted to be sounded in harmony with the sound produced by the piano on playing a 105 key. Thus if the note of C is played by

pressing the corresponding key D the corresponding note C is played on one of the instruments above mentioned.

The electromagnet H is employed for actuating the sounding devices N' of the orchestra bells N; the electromagnet I is used for actuating the fingering devices O for fingering the strings L', L², L³ and L⁴ of the violin L, while the electromagnet J is used for moving revoluble wheels P into engagement with the corresponding strings L', L², L³, L⁴ for sounding the latter. The several wheels P are continually rotated and are preferably driven from an electric motor Q electrically connected with the source of electrical energy G², as plainly indicated in Fig. 2.

Each sounding device N for the orchestra bells is in the form of a hammer attached to the free end of a spring armature lever H' for the corresponding electromagnet H, the armature lever being normally in the position shown in Figs. 2 and 3 with the hammer suspended above the corresponding bar, of the orchestra bells N. When the electromagnet H is energized on closing the circuit by pressing the corresponding piano key D then the armature lever H' is attracted and the hammer N' strikes and sounds the bell, the sound corresponding to the sound produced by the piano. The return movement of the armature lever H' is limited by a stop rail H² supported by brackets H³ from the frame H attached to the casing K. When it is desired to cut out the orchestra bells and only sound the violin in conjunction with the piano, then the armature levers H' are locked in retracted position by the use of hooks H⁴ fulcrumed on the casing K (see Figs. 13 and 14). The several hooks H⁴ are pivotally connected with a bar H⁵ extending lengthwise of the casing K and under the control of the player to normally hold the hooks H⁴ out of engagement with the armature levers H'. When it is desired to cut out the orchestra bells, the player shifts the bar H⁵ to impart a swinging motion to the hooks H⁴ so as to engage the same with the armature levers H' and to hold the same against movement whenever the corresponding electromagnet H is energized.

The fingering devices O for fingering the strings L', L², L³ and L⁴ of the violin L consist of a number of levers O', of which eight are adapted to engage the first string L' of the violin L a semitone apart, six levers engage the second string L² a semitone apart, six levers engage the string L³ a semitone apart, and a single lever engages the string L⁴ at the note C to correspond to the middle note C of the piano. The levers O' are each provided at one end with an armature I' adapted to be attracted by the corresponding magnet I whenever the lat-

ter is energized when the circuit is closed on the player pressing a corresponding key D. The other end of each lever O is provided with a block O² having a V-shaped groove extending under the string L', L², L³ or L⁴, so that when the lever O receives a swinging motion by the action of its electromagnet I then the block O² engages the string. A spring O³ is connected with each lever O to return the same to normal position as soon as its electromagnet I is de-energized, the return swinging movement of the lever being limited by a stop O⁴.

Each of the sounding wheels P has its peripheral face formed of hairs, bristles or similar filamentous means P', curved backward, that is, in a reverse direction from which the wheel P is rotating, the said hairs P' being attached to a solid center P² secured to the spring terminal P³ of a shaft P⁴ journaled at one end in a bearing R and at its other end in a bearing J' forming part of the armature J² for a corresponding electromagnet J. Each armature J² for the electromagnet J is hung on springs S (see Fig. 11) to normally hold the armature J² above the cores of the electromagnet J. When the bearing J' is in this position the corresponding sounding wheel P is above its corresponding string L', L², L³ or L⁴, but when the electromagnet J is energized on closing the circuit, by the operator pressing the corresponding key D, then the armature J² moves downward and in doing so imparts a like swinging motion to the shaft P⁴ thus moving the wheel P in engagement with the corresponding string L', L², L³ or L⁴, to sound the same whether the latter is in open position or engaged by the corresponding fingering lever O', as previously explained. When the piano key is released and the circuit is broken the armature J² returns to normal uppermost position by the action of the spring S, the upward movement of the armature being limited by stop screws S' screwing in a bracket R' having a keyhole R² through which extends a reduced portion P⁵ of the shaft P to guide the latter in its downward movement at the time the armature J² is attracted by the electromagnet J, as previously explained. It is understood that each wheel P rotates continually and by mounting it on the spring terminal P³ of the shaft P⁴ it is evident that a proper contact of the wheel with its string is had whenever the electromagnet J is energized.

In order to rotate the shafts P⁴ from the motor Q the following arrangement is made: On the motor shaft Q' is secured a sprocket wheel T connected by a sprocket chain T' with a sprocket wheel T² secured on the shaft P⁴ carrying the sounding wheel P for the first string L' of the violin L. When the motor is running, a continuous

rotary motion is given to the shaft P^4 just mentioned and the rotary motion of this shaft is transmitted to the other shaft P^4 by sprocket wheel and chain connection T^3 to rotate the several shafts P^4 in unison.

In practice, the piano keys from the middle C upward are used for closing the electric circuits for the several actuating devices used for sounding the bells N and for 10 operating the fingering levers O'.

It is understood that the single fingering lever O' for the fourth (G) string L', see Fig. 7, is located at the third finger position to play the low C note, while the last 15 lever O' for the first (E) string L' is located at the last finger position, as indicated in Fig. 6, to play the high C note when the corresponding keys D for low and high C are pressed.

Having thus described my invention, I claim as new and desire to secure by Letters Patent:

1. In combination with a piano having keys and sounding devices controlled by the 25 said keys, a second musical instrument of the violin type, fingering devices for fingering the strings of the said second musical instrument, string-playing devices adapted to engage the said strings to sound the same, 30 orchestra bells, electric circuits having circuit-closers controlled by the said piano keys, electric actuating devices connected with the said fingering devices, electric controlling devices for the said string-playing 35 devices and electric actuating devices for sounding the orchestra bells, the said circuits being connected with the actuating and controlling devices to sound a string, and a bell in harmony with the corresponding 40 sound of the piano on playing a piano key.

2. In combination with a piano having keys and sounding devices controlled by the said piano keys, a second musical instrument of the violin type, pivoted fingering 45 levers for fingering the strings of the said musical instrument, electromagnets for actuating the said fingering levers, continually driven filamentous sounding wheels adapted to be moved into engagement with the said 50 strings of the second instrument, electromagnets for moving the said sounding wheels into engagement with their strings, and electric circuits having circuit closers controlled by the said piano keys and electrically connected with the said electromagnets to sound a string of the second musical 55 instrument in harmony with a string of the piano on playing a piano key.

3. A musical instrument of the violin type 60 having strings, fingering levers adapted to finger the said strings, an electromagnet for actuating each fingering lever, sounding wheels adapted to be moved into engagement with the said strings, continuously 65 driven shafts having spring terminals car-

rying the sounding wheels, a movable bearing for each shaft, electromagnets, the armatures of which are secured directly to said bearings, normally open electric circuits for the said electromagnets, and means for closing the said circuits to simultaneously actuate a fingering device and a bearing for fingering a string and sounding the same string by the corresponding sounding wheel.

4. The combination with a violin, of pivoted fingering levers on opposite sides of the neck of the violin, an electro-magnet for operating each lever, a filamentous sounding wheel adapted to be moved into 70 engagement with each string of the violin, continuously revolving shafts carrying the said wheels, a bracket provided with slots through which the shafts loosely project, electro-magnets, armatures for the magnets, 75 yielding supported from the bracket and in which the said shafts are mounted.

5. The combination with a piano, of a violin, pivoted and spring-pressed fingering levers, each carrying a block at one end for 80 engaging a string of the violin, electro-magnets, the armatures of which are carried by the other ends of the said levers, string-playing 85 wheels adapted to engage the strings, continuously rotating shafts carrying said 90 wheels, electro-magnets, the armatures of which carry bearings in which the ends of the shafts are mounted, and branch circuits having circuit-closers controlled by the keys 95 of the piano, said branch circuits including 100 said electro-magnets.

6. The combination with a piano, of a violin, pivoted fingering levers, electro-magnets, the armatures of which are on one end of the levers, string playing wheels, continuously rotating shafts carrying the 105 wheels, electro-magnets, the armatures of which carry bearings in which the shafts are mounted, orchestra bells, electro-magnets, the armatures of which carry springs, sounding 110 devices for the bells secured to the ends of the springs, and branch circuits having circuit closers controlled by the keys of the piano, said branch circuits including said electro-magnets.

7. The combination with a piano, a violin, fingering devices for the strings, string-playing devices for said strings, electrical actuating devices for the fingering and playing devices and branch circuits connected 115 with the actuating devices and having circuit-closers controlled by the keys of the piano, of orchestra bells, electro-magnets in the said circuits, spring levers carried by the armatures of the magnets, sounding devices 120 for the bells on the free ends of the spring levers, and means for locking the spring levers to cut out the orchestra bells.

8. In a musical instrument of the character described, the combination of orches- 130

tra bells, tuned to furnish a musical scale, branch circuits, electro-magnets in the said circuits, a spring lever carried by the armature of each magnet, a hammer on the end of each spring lever, and a hook for engaging each spring lever to lock it in inoperative position.

In testimony whereof I have signed my name to this specification in the presence of two subscribing witnesses.

DONALD PATRICK MUSE.
